SNAP SWITCH

Charles F. Coake, Indianapolis, Ind.

Application January 20, 1948, Serial No. 3,322

4 Claims. (Cl. 200—67)

1

This invention relates to snap switches and more particularly to switches of the micro-switch type which are adapted to be actuated by a plunger having a limited range of movement.

An object of the invention is to provide a switch of the above type having novel and improved details of construction and features of operation.

Another object is to provide a switch of the above type which is composed of a minimum number of parts.

Another object is to provide a novel and improved reed construction for a switch of the above type.

Another object is to provide an integral reed and actuating spring for use in a switch of the above type.

Various other objects and advantages will be apparent as the nature of the invention is more fully disclosed.

In accordance with the present invention, the actuating spring is made integral with the reed and is designed to produce a toggle action which causes the actuating spring to snap from one position to the other when the end of the spring is shifted past its central balanced position. The switch may be single acting or double acting depending upon the range of movement permitted.

In one embodiment the actuating spring is stamped out of the reed in the form of a central tongue which is coiled about the free end of the reed with its free end brought into engagement with an abutment on the actuating arm. The spring is held under compression by the actuating arm and is shifted thereby from one side to the other of its central or balanced position for obtaining the snap action.

Although the novel features which are characteristic of this invention are pointed out more particularly in the claims, the nature of the invention will be better understood by referring to the following description taken in connection with the accompanying drawings in which certain specific embodiments thereof have been set forth for purposes of illustration.

In the drawings:

Fig. 1 is a side elevation of a switch embodying the present invention, with the housing shown in section;

Fig. 2 is a view similar to Fig. 1 showing the switch in open contact position;

Fig. 3 is a top plan view of the switch of Figs. 1 and 2 with the cover removed;

Fig. 4 is detail view of the reed blank;

Fig. 5 is a side elevation similar to Fig. 1 showing a further embodiment of the invention;

Fig. 6 is a detail view of the reed shown in Fig. 5;

2

Fig. 7 is a side elevation similar to Fig. 1 showing a still further embodiment of the invention;

Fig. 8 is a detail view of the reed shown in Fig. 7; and

Fig. 9 is a plan view of the reed blank.

Referring to the drawings more in detail, the switch is shown in Figs. 1 to 4 as comprising a housing 10 and a cover 11 which are formed of suitable insulating material and are adopted to enclose a switch chamber 12.

The reed, as shown in Fig. 4, comprises a stamping formed with side arms 17, end flanges 20 and 21, and a central tongue 18 which extends from the end flange 20 toward the end flange 21. A short tongue 22 projects from the end flange 21 to provide space for a hole 23. The flange 21 of the reed is attached to a boss 16 formed in the housing 10 by a screw 15 passing through the hole 23.

20 The actuating spring is formed by first bending the end flange 20 upwardly to form a vertical flange as shown in Fig. 1 and thence curling the tongue 18 around the end flange 20 with its free end 25 extending toward the end flange 21 and

25 engaging an abutment 26 on a movable actuating arm 27 which is shown in the form of a leaf spring having a fixed end 28 secured to the boss 16 by the screw 15 and having an S-shaped bend at its free end forming the abutment 26.

30 A plunger 29 slidably mounted in the cover 11 engages the actuating arm 27 at a point spaced from the fixed end 28 thereof by an amount dependent upon the leverage desired and the amount of throw of the plunger.

35 For making electrical contact with the reed the screw 15 engages a metal ferrule 30 extending through the boss 16 and carrying an external contact screw 31. A fixed contact 40 is carried by a pin 41 extending through a boss 42 in the housing 10 and carrying nuts 43 by which an external conductor 44 is attached. The movable contact 45 is carried by the actuating spring 18.

40 The actuating arm 27 is sufficiently resilient to retract the plunger 29 and to return to its upward position as shown in Fig. 1 when the pressure on the plunger is released. The coiled spring 18 is so arranged that it is held under compression by the abutment 26 so that it tends to snap in one direction or the other as the end 25 is

45 shifted by the abutment 26 past the central or balanced position. In the position shown in Fig. 1, the free end 25 of the spring 18 is located above its balanced position causing the spring 18 to snap downwardly and close the contact 45, the

50 reed arm 17 also flexing about its fixed end in response to the downward force supplied by the coiled spring 18.

55 As the actuating arm 27 is flexed downwardly by depressing the plunger 29, the free end 25 of the spring 18 is shifted downwardly past the

balanced position to the position shown in Fig. 2, whereupon an upward force is produced which causes the spring 18 to snap into its upper position, flexing the arms 17 of the reed and opening the contact 45. The contact 45 thus opens with a snap action and the extent of opening is independent of the amount of movement of the plunger 29.

For a make and break switch, as shown, the actuating arm 27 is adapted to return to its original position when the pressure on the plunger 29 is released, thereby causing the contact 45 to again close with a snap action when the free end 25 of the spring 18 passes its central position. There is also a wiping action between the contacts 45 and 40 produced by the flexing of the spring 18.

The upward movement of the spring 18 is limited by a boss 46 formed on the cover 11. If desired a contact may be carried at this point for forming a double throw switch. Likewise the throw may be made adjustable by the provision of an adjusting screw 47. If it is desired to provide a construction wherein the switch reed remains in either actuated position, the actuating arm 27 may be made of non-resilient material in which case a separate plunger may be used to restore the arm 27 when it is desired to reclose the contact 45.

Inasmuch as the action of the reed is dependent upon the characteristics of the arms 17 and spring 18, the unitary construction insures that these elements which are stamped out of the same blank will always have the same relative characteristics. Hence the reed may be made uniform in action without the necessity of carefully checking the reed arms against the springs as would be required if they were made of separate elements. The cost of assembly of the switch is also decreased due to a reduction in the number of parts which would otherwise be required. The switch is accordingly well adapted to volume commercial production.

Referring to Figs. 5 and 6, the construction is generally similar to that of Figs. 1 to 4 and the corresponding parts have been given the same reference characters. In this embodiment, however, the spring 18a has been bent into an S-shape with its free end 25 engaging abutment 26 as before. The spring 18a in this case does not extend around the end flange 20 of the reed, but extends between the arms 17 toward the fixed end thereof. The same toggle action is obtained as in the form of the invention above described.

Referring to Figs. 7, 8 and 9 a composite reed, spring, and actuating arm are formed in a single stamping. In this embodiment the parts corresponding to those in Figs. 1 to 4 have also been given the same reference characters. The tongue 18b in this instance, however, extends outwardly beyond the arms 17, as shown in Fig. 9, and the actuating arm 27b is formed integrally with the arms 17 of the reed and extends from the fixed end of the reed toward the free end thereof. The reed is assembled by bending the actuating arm 27b upwardly and then downwardly to form the abutment 26 as shown in Fig. 7 and by coiling the tongue 18b around the end flange 20 of the reed with its free end 25 engaging the abutment 26 of the actuating arm 27b.

The operation of this form of the invention is also similar to that described above, the spring 18b coacting with the actuating arm to flex the reed upwardly and downwardly when the free end

25 of the spring 18b is shifted past its central balanced position. This form has the further advantage of reducing the switch elements to a single part which may be stamped from a blank in the form shown in Fig. 9 and is adapted for use by merely flexing the elements into the form shown in Fig. 7.

The switch may be adapted for use as a thermostat by replacing the actuating arm 27 of Fig. 1 with a bimetallic thermostatic element which is adapted to flex in response to changes in temperature.

Although certain specific embodiments of the invention have been shown for purposes of illustration, it is to be understood that various changes and adaptations may be made therein, as will be readily apparent to a person skilled in the art. The invention is only to be restricted in accordance with the scope of the following claims.

What is claimed is:

1. A snap switch comprising a spring reed having a fixed end and a free end, an actuating spring comprising a tongue formed integral with said reed and having one end fixed to the free end of said reed said tongue being curled around the free end of said reed and having a free end extending toward the fixed end of said reed, a movable actuating arm having a fixed end mounted adjacent the fixed end of said reed and having a free end extending toward the free end of said reed, said actuating arm having an abutment engaging the free end of said tongue and arranged to hold the tongue flexed and under compression so that a toggle action is obtained for shifting said actuating spring with a snap action as the free end of the actuating arm is shifted transversely of said reed past a balanced position.

2. A snap switch comprising a spring reed having a fixed end and a free end, an actuating spring comprising a tongue formed integral with said reed and having one end fixed to the free end of said reed and having a free end extending toward the fixed end of said reed, a movable actuating arm having a fixed end mounted adjacent the fixed end of said reed and having a free end extending toward the free end of said reed, said actuating arm having an abutment engaging the free end of said tongue and arranged to hold the tongue flexed and under compression so that a toggle action is obtained for shifting said actuating spring with a snap action as the free end of the actuating arm is shifted transversely of said reed past a balanced position, a movable contact carried by said tongue, a fixed contact cooperating therewith, and means making an electrical connection to said reed.

3. A snap switch as set forth in claim 2 in which said tongue is coiled around said last end flange.

4. A snap switch as set forth in claim 2 in which said tongue is bent into S shape and projects between said side arms toward said fixed end.
